SHOE RACK

Paul Jones, Whitman, Mass., assignor to United Shoe Machinery Corporation, Paterson, N. J., a Corporation of New Jersey

Application November 6, 1930. Serial No. 493,833

7 Claims. (Cl. 211—34)

This invention relates to shoe racks such as are used for transporting shoes from one part of a factory to another and for holding shoes between operations performed upon them.

One type of shoe rack which has been extensively used in the past comprises a series of spaced shoe-supporting dowels or pins, the edge portions of adjacent pins being arranged to engage and support opposite sides of a shoe carried bottom side up in the rack. A shoe carried in a rack of the type referred to makes substantially line contacts with the edge portions of the pins and, because of the irregularities of the surfaces of the shoes, the latter engage the pins over small areas only with the result that the entire weight of a shoe is concentrated upon correspondingly small portions of its upper. This frequently results in denting or otherwise marring the upper.

An object of the present invention is to provide an improved shoe rack which will be especially adapted to carry shoes without likelihood of damaging the uppers of the shoes. Accordingly, and as illustrated, the invention provides a rack comprising shoe-supporting members or pins having surfaces for engaging opposite sides of the upper of a shoe positioned between the surfaces, and in which the surfaces of the pins are inclined at different angles to a plane passing through the pins in order closely to engage opposite sides of the shoe. Preferably, and as shown, the pins are arranged in series and the shoe-engaging surfaces of the pins are substantially flat, some of the surfaces being so angularly disposed that they will closely engage inner portions of the uppers of shoes carried by the surfaces and others of the surfaces being differently disposed angularly to engage closely outer portions of the uppers of the shoes. By the use of the construction above indicated, shoes are carried with the opposite side portions of their uppers resting upon comparatively large areas of the supporting surfaces with the result that the weight of each shoe is distributed over correspondingly large areas of contact, thereby avoiding such contact of the uppers with supporting members as would indent the uppers to the extent of injuring them. This construction thus makes it possible to support shoes having uppers made of delicate leather without danger of marring the shoes.

Other objects and features of the invention will be apparent from the following description when taken in connection with the accompanying drawings and will be pointed out in the claims.

In the drawings,

Fig. 1 is a perspective view of a shoe rack constructed according to the invention; and

Fig. 2 is a perspective view of a portion of the rack, looking down upon the pins at an angle of approximately 45° thereto and illustrating the manner in which shoes are carried upon the pins.

As illustrated in the drawings, the shoe rack comprises a metal frame 10 in which are secured a plurality of wooden shelves 12 each comprising a back-rail 14 and a central support 16 extending parallel to each other and connected at their ends to bars 18 which in turn are held in the frame 10 by clips 20. The members 14 and 16 carry a plurality of shoe-supporting members 22 and 24 which are illustrated as pins the axes of which lie in substantially the same plane and the inner ends of which are turned down to form shank portions 26 which extend through and are rigidly secured to the members 14 and 16. The pins 22 and 24 are arranged in series with two adjacently disposed pins 22 alternating with a single pin 24 throughout the length of the rack except at each end thereof where only a single pin 22 is used. The spaces between each pin 24 and the next adjacent pins 22 upon each side thereof are such as to provide for the insertion of a pair of shoes, bottoms up, with opposite sides of the upper of each shoe resting respectively upon a flat side surface 28 of a pin 22 and a flat side surface 30 of a pin 24.

The outer end of each of the pins 22 is substantially rectangular in cross-section and is positioned with one of its flat side surfaces, namely surface 28, which constitutes the shoe-engaging portion of the pin, facing upwardly and disposed at an inclination to the plane passing through the axes of the pins 22 and 24. The outer end of each of the pins 24 is substantially triangular in cross-section with the apex of the triangle uppermost with the result that the flat side surfaces 30, which constitute the shoe-engaging portions of the pin, face upwardly and extend at an inclination to the plane referred to.

The angle between the upwardly disposed flat surfaces 30 of the members 24 corresponds approximately to the angle between the side surfaces of two shoes, of the style of shoes to be carried, positioned with their bottoms in the same plane and with the inner portions of the uppers adjacent. The angle between adjacent upwardly facing flat surfaces 28 of members 22 similarly corresponds to the angle between the outer side surfaces of uppers of shoes positioned with their bottoms in the same plane and their outer surfaces adjacent, and, since the outer portions of

the uppers of shoes are generally more flatly curved relatively to the bottom of the shoe than are the inner portions of the upper, the angle between adjacent surfaces 28 has been correspondingly made greater than that between surfaces 30. In other words, the surfaces 30 extend at a greater inclination to the plane passing through the axes of the pins than do the surfaces 28. A shoe, such as shoe 32 (Fig. 2), is carried in the rack bottom up with the inner side portions of the upper of the shoe engaging the flat surface 30 of the member 24, and the outer surfaces of the upper of the shoe engaging the flat surface 28 of the adjacent member 22. Since the inclinations of the surfaces 28 and 30 are such as to correspond closely to the sides of the upper which they engage, the shoe will make contact over considerable areas of the surfaces and will, accordingly, rest evenly upon them.

The distance between each of the pins 24 and adjacent pins 22 is such that the largest shoes to be carried between such pins will ride sufficiently low upon the pins that there will be no likelihood of contact between adjacent shoes. However, in order to effect economy in the size of the rack and particularly in the length thereof, adjacent members 22 and 24 are placed close together but sufficiently spaced so that shoes of the maximum size to be carried will not engage each other. For the same reason adjacent members 22 are placed close together, the distances between the top edges of such members being great enough so that the outward bulges of adjacent shoes in contact with such members will not engage each other. In practice, it has been found that shoes can be carried with their inner edge portions very close together, without any likelihood of their contact, upon adjacent surfaces such as surfaces 30. It is because of this that each of the pins 24 is provided with two shoe-engaging surfaces 30, thus effecting economy in manufacture.

In the operation of the rack, shoes are placed bottoms up upon the pins 22 and 24 with the upper of each shoe in engagement with adjacent surfaces 28 and 30 in the manner above described, the shoes of themselves sinking down into the troughs formed by the pins until the sides of the uppers of the shoes rest evenly upon surfaces of the pins and the toe portions of the foreparts rest upon the supports 16. In such positions the shoes will be securely held against lateral movement relatively to the pins, and contact between adjacent shoes, which might tend to injure the uppers, is prevented. Since the side surfaces of the shoes rest entirely upon the flat surfaces of the pins, there will be no likelihood of the shoes being marred by engagement with edges of supporting members, and, since the weight of each shoe carried will be distributed over considerable areas of the upper, the likelihood of so indenting the upper as to damage an upper formed of delicate leather is practically eliminated.

Having described my invention, what I claim as new and desire to secure by Letters Patent of the United States is:—

1. A shoe rack comprising a plurality of shoe-supporting pins having flat surfaces arranged in pairs and inclined for engaging closely inner

portions of the uppers of shoes carried in the rack, and a plurality of shoe-supporting pins having flat surfaces arranged in pairs alternating with the first-mentioned pairs of surfaces and differently inclined for engaging closely outer portions of the uppers of shoes carried in the rack. 80

2. A shoe rack comprising a plurality of shoe-supporting pins arranged in series and having shoe-engaging surfaces arranged in pairs throughout the series with one of the surfaces of a pair of adjacent surfaces extending at an inclination to a plane passing through the pins closely to engage the outer portion of the upper of a shoe positioned between the adjacent surfaces and the other of the adjacent surfaces extending at a different inclination to the plane closely to engage the inner portion of the upper of the shoe. 85

3. A shoe rack comprising a plurality of shoe-supporting members having shoe-engaging surfaces arranged in pairs with the surfaces of each pair of surfaces extending at an inclination to each other for closely engaging the inner portions of the uppers of adjacent shoes carried in the rack, and a plurality of shoe-supporting members having shoe-supporting surfaces arranged in pairs between successive pairs of the first-mentioned pairs of surfaces and in which the surfaces of each pair of surfaces extend at a different inclination to each other for closely engaging the outer portions of the uppers of adjacent shoes. 90

4. A shoe rack comprising a plurality of shoe-supporting members having flat surfaces arranged in pairs, the surfaces of some of the pairs of surfaces being disposed at an inclination to each other for closely engaging the inner side portions of shoes positioned in the rack closely adjacent but out of contact, and surfaces of others of the pairs of surfaces being disposed at a different inclination to each other for closely engaging the outer side portions of shoes positioned in the rack closely adjacent but out of contact. 100

5. A shoe rack comprising a plurality of shoe-supporting pins arranged in series and having shoe-engaging surfaces arranged with the alternate surfaces throughout the series extending at different inclinations to a plane passing through the pins. 105

6. A shoe rack comprising a series of shoe-supporting pins the axes of which lie substantially in the same plane, the pins having shoe-engaging surfaces parallel to the axes and so arranged that the angle formed between any pair of adjacent surfaces throughout the length of the rack is different from the angle formed between either of the surfaces of the pair of surfaces and the next adjacent surface. 115

7. A shoe rack comprising a plurality of shoe-supporting pins having flat shoe-engaging surfaces arranged in pairs with the surfaces of each pair of surfaces converging upwardly toward each other, the surfaces of alternate pairs of surfaces being inclined toward each other at an angle greater than the angle included between the surfaces of each of the other pairs of surfaces. 120
